UNITED STATES PATENT OFFICE.

JULIUS H. BENKOWITZ, OF CHICAGO, ILLINOIS.

MAILING DEVICE.

1,324,100.

Specification of Letters Patent.

Patented Dec. 9, 1919.

Application filed March 8, 1917, Serial No. 153,496. Renewed August 27, 1919. Serial No. 320,303.

To all whom it may concern:

Be it known that I, Julius H. Benkowitz, a citizen of the United States, and a resident of Chicago, Cook county, Illinois, have invented certain new and useful Improvements in Mailing Devices, of which the following is a specification:

My invention relates generally to improvements in mailing devices and relates more particularly to improvements in mailing devices designed for transmission from sender to recipient and from recipient to sender.

The general object of my invention is to provide a device of the above character which can be manufactured cheaply and with little waste of stock; and a further object of my invention is to provide a mailing device of the above character wherein the work required on the part of the recipient to redespach same shall be almost negligible.

Other objects of my invention will appear hereinafter.

My invention consists generally in the form, construction and co-operation of the parts whereby the above named objects, together with others which will appear hereinafter, are attainable; and my invention will be more readily understood by reference to the accompanying drawings which illustrate preferred embodiments thereof. In said drawings, I have chosen to depict my invention as embodied in an envelop and therein,

Figure 1, is a view of an envelop embodying my invention;—

Fig. 2, is a view of the envelop shown in Fig. 1, in condition for initial mailing;—

Fig. 3, is a view of the envelop in the condition shown in Fig. 2, but viewed from the opposite side;—

Fig. 4, is a view of the envelop of Fig. 1, in condition for its return journey from recipient to sender;—

Fig. 5, is a view illustrating a modification of my invention;—

Fig. 6, shows the envelop of Fig. 5, in condition for initial mailing;—

Fig. 7, is a view of the envelop of Fig. 6, viewed from the reverse side.

I am aware that it has hitherto been proposed to provide an envelop which may be used several times, as for example, for the purpose of sending and returning. The envelops hitherto devised for this purpose,

however, have been of such construction or character as either to be expensive in manufacture or to require considerable action upon the part of the recipient before the envelop is suitable for return purposes. 60 Either or both of the above conditions are extremely detrimental to the practical utility of a device of this kind, the object thereof being materially to reduce the cost of communication both in respect to the manufacturing cost of the envelop itself which comprises such items as the stock, printing, scoring, etc., and the cost of postage which is dependent upon the character and the amount of the material employed. To overcome the above objections I have devised an envelop which is at once cheap to manufacture, which comprises but little stock, and wherein the recipient need perform but a simple act in order to return the envelop. 75 It is recognized in the advertising art that any device which will reduce the operations necessary on the part of the desired customer and make it convenient to respond are of the utmost value. An envelop of the 80 kind under consideration is employed largely in advertising campaigns, and hence the above mentioned advertising psychology is applicable thereto. I have also devised an envelop which can be manufactured with 85 the usual envelop machinery.

In the embodiment of my invention shown in Figs. 1 to 3 I provide an envelop of desired size having a body portion, 40, and a flap portion 41, of substantially the same 90 size. Upon the face 42, which is adapted to be covered by the flap I provide the name of the sender as indicated at 43, and also the name of the recipient as indicated at 44, together with the word "From" or the word of 95 similar import. I may also provide a stamp for the return of the envelop, or a place for such stamp at the position indicated by the numeral 45. I cut out a portion of the flap, as indicated at 46, so that when the flap is 100 folded over the face 42, it will disclose only the address, 44, hiding the other printed matter. The flap is provided with two gummed portions 47 and 48, and the gummed portion 47 is used for the initial 105 sealing of the envelop. 49, indicates the position for the postage covering the envelop on its initial journey. For convenience, in opening the envelop, and removing a part of the flap portion of the envelop for its re- 110

turn trip, I prefer to score the flap along the dotted lines 50 and 51, and to cut away the corners of the flap as indicated at 52. The portion of the flap between the lines 50 and 51, is removed by recipient in opening and in adapting the envelop for its return journey, which can be conveniently accomplished by severing along the line 50, and then pulling on the loose flap portion thus produced.

10 In returning the envelop the gummed zone 48, is used to seal the envelop so that upon its return journey it appears as indicated in Fig. 4. The initial sending address, it should be noted, now serves as a return address, and also serves to inform the original sender of the name and address of the original recipient. I might here state also that the reverse face portion 55, of the envelop may carry an advertisement of the sender on both the initial and return journeys, as this face is not needed for other purposes (see Fig. 3).

That form of my invention shown in Figs. 5, 6 and 7, differs from the form just described in the construction of the sealing flap. In this instance the sealing flap is of such size as to extend across the face portion 42, of the envelop and to provide an extending portion 60, which can be folded over the edge and sealed upon the face, 55. The flap is gummed at 61 and 62, the gummed portion 61, being used for initial sealing and 62, for return sealing. I prefer to cut away a portion of each side of the flap, as indicated at 52, to form a convenient opening for the insertion of an envelop opener. The envelop can be thus easily opened along the edge and the flap-portion removed along the line 50, for return purposes.

40 Under some conditions instead of gumming the flaps for fastening purposes, I may provide fastening means of other suitable character. My invention is not to be considered limited to an envelop, but to embrace also other mailing devices, except only 45 when expressly so limited in the claims.

I claim:

1. A mailing device having a body portion and a flap portion, two addresses on the body portion over which the flap is adapted to fold, said flap being separable into parts and having an opening positioned to disclose one of the addresses when folded upon the body, said disclosed address initially serving as a directing address and serving as a return address by the mere act of removing a portion of the flap.

2. A mailing device having a body portion and a flap portion, two addresses on the body portion over which the flap is adapted to fold, one of said addresses having a legend associated therewith indicating the source of origin of the device, said flap being divided into conveniently separable parts and having an opening positioned to disclose the address having the associated legend, but to hide the legend, said disclosed address and legend serving as a return address by the mere act of removing the separable part of the flap.

3. A mailing device having a body portion and a flap portion, the flap portion carrying spaced fastening means, two addresses on the body portion over which the flap is adapted to fold, one of said addresses having a legend associated therewith indicating the source of origin of the device, said flap being divided into conveniently separable parts and having an opening positioned to disclose the address having the associated legend, but to hide the legend, said disclosed address and legend serving as a return address when a separable part of the flap is removed.

In testimony thereof I have hereunto set my hand, this 24th day of February, 1917, in the presence of two subscribing witnesses.
